UNITED STATES PATENT OFFICE.

LOUIS HARLOW, OF EAST MILTON, MASSACHUSETTS, ASSIGNOR TO BROWN DAISY PRODUCTS COMPANY, OF BOSTON, MASSACHUSETTS, A CORPORATION OF MASSACHUSETTS.

MOP.

1,215,270.

Specification of Letters Patent.

Patented Feb. 6, 1917.

Application filed March 15, 1912. Serial No. 683,954.

To all whom it may concern:

Be it known that I, LOUIS HARLOW, a citizen of the United States, and resident of East Milton, county of Norfolk, State of 5 Massachusetts, have invented an Improvement in Mops, of which the following description, in connection with the accompanying drawing, is a specification, like characters on the drawing representing like parts.

10 This invention relates to the construction of a mop, and particularly the kind of mop composed of yarn and used for wiping floors.

The object of the invention is to provide 15 a device of this character in which the yarn or mop fabric is firmly held in place and prevented from pulling out during the use of the mop, and in which there is no danger of the wooden or metallic parts of the mop head coming in contact with the floor.

20 The nature of the invention will more fully appear in the accompanying description and drawings, and will be particularly pointed out in the appended claims.

The drawings represent the preferred 25 form of the invention embodying a cross-head mop of a usual type.

In the drawings

Figure 1 is an end view of the mop;

Fig. 2 is a front view of the mop;

30 Fig. 3 is a longitudinal vertical cross section of the mop head;

Fig. 4 is a transverse vertical cross section of the mop head.

The mop is shown as comprising the usual 35 handle 1, secured to the crosshead 2 of generally cylindrical shape, and extending transversely of the handle. These parts are as usual made of wood.

The mop head on its bottom is recessed 40 longitudinally as clearly appears from Figs. 3 and 4, and this recess is deep and wide and is shown as of generally rectangular cross section.

The mop proper is shown as composed of 45 yarn 3. The yarn strands, or whatever other material the mop may be composed of, is laid transversely between two long narrow metallic plates 4 and 5. These plates are of the same length as the recess in the mop 50 head, and sufficiently narrower than the recess to allow them with the interposed mop fabric to be crowded into the recess. The mop fabric is clamped in place between the plates 4 and 5 and secured by riveting the 55 plates together as indicated at 6.

One of the clamping plates, preferred the lower one 4, has its ends bent upwardly to form ears 7, which extend up against and fit in corresponding recesses in the ends of the mop head. The clamping plates with 60 the interposed mop fabric are held in place in the recess by securing the ears firmly to the mop head. The means shown for this purpose are screws 8 passing through apertures in the ears and into the wooden mop 65 head. Buffers 9, shown as rubber buttons, are also secured to the ends of the mop head by the screws 8.

It will be seen that when the parts are assembled the metallic clamping plates are 70 seated in the recess in the mop head above the bottom surface of the wooden portion of the mop head, and at the same time they hold the mop fabric in such a position as to prevent any portion of the mop head from 75 coming in contact with and scratching or injuring the floor. The buffers on the ends of the mop head likewise prevent the ends of the mop head from scratching or injuring the floor or walls.

The construction is simple, efficient and durable. Not only is injury to the walls and floor prevented, but the mop fabric is so firmly held that it will not come out or be pulled out in use.

85 The construction of this invention enables the mop fabric with the clamping plates to be removed readily and easily from, and replaced in, the crosshead. This is done by the aid of an ordinary screw driver by removing and replacing the screws 8 and buffers 9. Not only can the mop fabric be readily washed or cleaned when thus removed but the mop fabric and clamping plates may be removed without the necessity of removing the cross head and handle.

Having fully described my invention, what I claim as new and desire to secure by Letters Patent is:—

1. A mop comprising a head having a 100 longitudinal recess in its bottom, a clamp removably positioned in said recess and adapted to retain a mop fabric, said clamp being composed of an upper and a lower clamping member, said upper member being 105 carried by said lower member, arms on said lower member whereby said clamping members are removably suspended in said recess, and means for securing said members together to retain therebetween a mop fabric. 110

2. A mop comprising a head having a longitudinal recess in its bottom; a clamp demountably positioned in said recess and adapted to retain a mop fabric; said demountable clamp being composed of two parallel bars, a supporting bar and a carried bar; means for securing said carried bar to said supporting bar, supporting arms on each end of said supporting bar, said arms 10 being upturned at an angle to the plane of said bars, and means carried by said head demountably to suspend said arms from said head, whereby said mop-retaining clamp may be easily demounted from said head 15 for cleansing or for substitution.

3. A mop comprising a head having a longitudinal recess in its bottom and vertical end recesses; a clamp demountably positioned in said longitudinal recess and composed of parallel bars, a lower supporting bar and an upper carried bar; rivets adapted permanently to secure said upper bar to said lower bar and to cause said bars cooperatively to retain a mop fabric; arms 20 on said lower bar upwardly extended and adapted to be positioned in said end recesses; and means for demountably securing said arms in said end recesses; whereby said 25

mop-retaining clamp may be demounted from said recess for substitution or for mop 30 fabric cleansing.

4. A mop comprising a head having a longitudinal recess in its bottom; a clamp demountably positioned in said recess and composed of two parallel metal bars including a supporting bar and a carried bar; a plurality of rivets adapted permanently to secure said carried bar to said supporting bar whereby a mop fabric is retentively held therebetween; integral arms on each 35 end of said supporting bar, said arms being upturned at an angle to the plane of the bars and having apertures in their upper portions; screws adapted to be inserted through said apertures and to engage said head 40 whereby said arms are demountably secured to said head and said clamp may be removed from said head for substitution or mop cleansing.

In testimony whereof, I have signed my 50 name to this specification, in the presence of two subscribing witnesses.

LOUIS HARLOW.
